UNITED STATES PATENT OFFICE.

ALVIN HURFORD, OF CANTON, OHIO.

TRAP-DOOR FOR MINES.

SPECIFICATION forming part of Letters Patent No. 657,985, dated September 18, 1900.

Application filed November 4, 1897. Serial No. 657,819. (No model.)

To all whom it may concern:

Be it known that I, ALVIN HURFORD, of Canton, Stark county, Ohio, have invented certain new and useful Improvements in 5 Trap-Doors for Mines; and I do hereby declare the following to be a full, clear, and exact description of the invention, such as will enable others skilled in the art to which it pertains to make and use the same.

10 My invention relates to trap-doors for mines; and it consists in certain features of construction, which will be hereinafter fully set forth and claimed.

The object of this invention is to provide 15 means for automatically opening and closing trap-doors employed throughout the various passages and airways of coal-mines for the purpose of controlling the circulation and distribution of the artificially-generated ventilating air-currents. In order to interfere as little as possible with said ventilating system, it is necessary that the trap-doors be rapidly opened and closed at the time of the passage therethrough of the numerous cars and teams 20 employed in hauling the products of the mine. By my improved mechanism, as will be hereinafter seen, the desired results in the operation of said doors are cheaply and effectually obtained, said mechanism comprising, 25 essentially, a piston working and guided in a suitable cylinder and operated by steam, air, or hydraulic power, means for connecting said piston with the door or curtain to be operated, and automatic devices adapted to 30 be operated by the passage of a car or team, whereby the supply of steam, air, water, or other motive power to said cylinder and piston is regulated.

In carrying out my invention I preferably 40 use a flexible curtain of such length and width as effectually to close or trap a mine passage-way.

In the drawings, Figure I is a view in elevation illustrating the door and method of 45 operating the same. Fig. II is a view in side-elevation illustrating more clearly the mechanism employed. Figs. III and IV illustrate details of construction; and Fig. V illustrates the trip devices secured to the track and the 50 connection between the same and the valve which controls the supply of steam, air, or water to the operating-cylinder.

In the drawings, A A' represent posts located, respectively, at each side of a mine passage-way. These posts A A' are braced 55 or supported in any suitable manner to keep them in proper upright position, as by cross-beams or otherwise, and form the framework for supporting the roller or winding-drum C, to which is secured one end of the flexible 60 door or curtain D, arranged to wind or roll thereon. By the use of this flexible curtain I find that I obtain a light and easily operated trap or door not liable to get out of order. The roller or drum C is suitably journaled at 65 each end, respectively, in bearings B' B'', located at the upper part of framework A A'. D' represents a weight, preferably in the form of a rod, secured to the lower or free end of curtain D. This rod D', as shown in the drawings, is secured to the lower end of the curtain by forming a hem at the bottom of the curtain and inserting the rod therein; but it may be attached thereto in any suitable manner.

E represents a pinion rigidly secured to shaft C'.

F represents a rack adapted to mesh with pinion E, and by its reciprocating movement, as hereinafter described, it revolves the pinion 80 and roller C, and thus raises or lowers curtain D.

F' represents a housing which forms a guide for said rack F. This housing or guide F' is preferably secured to post A' opposite the 85 point of contact between rack F and pinion E in such a manner as to permit the free engagement of the same and maintain their operative relation.

G illustrates a piston-rod attached at its 90 lower end to a suitable piston (not shown in the drawings) operating in cylinder H. The piston-rod G is pivotally attached, as at f, to rack F, and hence it will be seen that as the piston-rod G is reciprocated the rack F moves 95 in the same direction, as illustrated in Fig. I of the drawings, and said rack F, as hereinbefore set forth, operates the pinion E and curtain-roller C, thus raising the curtain D, opening the trap, and allowing the car to 100 pass through.

Attached to the lower end of the cylinder H is a pipe H', communicating with the interior of said cylinder beneath the piston, to

which is secured the lower end of the piston-rod G. This pipe H' acts as a conveyer and feeder to supply the cylinder H and operate the piston. This medium may be steam, air, water, or the like.

5 H² represents a valve properly located in pipe H'. The valve H² is intended to control the medium—air, steam, water, or the like—passing through pipe H' and into cylinder H.

10 h represents a lever by means of which the valve H² is opened or closed.

J represents a track upon which the car-wheels run, the said car-wheels being provided with the usual tread and flange, as 15 shown by dotted lines in Fig. I.

K represents a curved lever located in juxtaposition to the track J and pivotally attached to the said track by means of a shaft k, which passes through the vertical part of 20 the track J. A collar or bushing k' is provided between the lever K and the track, as shown in Fig. I, and another collar or bushing k² is provided on the outside of the shaft k. This arrangement keeps the lever K in 25 proper position relative to the track and at the same time allows it to oscillate freely.

L represents a crank-lever secured to the outer end of the shaft k in such a manner as to operate said shaft, and thus operate the 30 lever K or be operated by the lever K, as the case may be.

M represents a pitman pivotally secured to the outer end of the lever L.

N represents a spring secured at one end 35 to the lever L and at its opposite end to a tie or other suitable connection or holding device. The function of the spring N is to retract the lever L after it has been raised by the car-wheel passing over the lever K and 40 bring the lever L, and with it the lever K, to the position indicated in Fig. IV of the drawings. When the lever K and the crank-lever L and its attached pitman are in the position shown in Fig. IV, the valve H² is 45 shut off or closed, and when the lever K is depressed it operates through lever L and pitman M to open valve H². This is accomplished through a suitable connection of levers and rods. (Illustrated more clearly in 50 Fig. V of the drawings.) The location of the curved lever K and its attached parts should be some distance along the track or passage before the trap is reached. Two track-levers and connecting devices or apparatus, like the

construction shown in Fig. IV, for engaging 55 the wheel of the car are preferably employed and located at both sides of the trap, and thus it will be seen that a car or train when passing toward the trap in either direction will operate, as hereinbefore described, to raise 60 the curtain. It will of course be understood that suitable connecting rods and levers communicate or intervene between the pitman M and handle of the valve H², and these connecting devices are so arranged as to cause 65 both trip-levers at either side of the curtain or shaft to operate in like manner and also to cause either or both of them to open valve H² and raise the curtain D.

In order to allow the curtain D to descend 70 or unroll from roller C after the car or train has passed through the trap-door, I provide a relief valve or cock h', located either in the cylinder H, behind the piston, or located in pipe H', between valve H² and the cylinder 75 H. This valve h' is so adjusted as to allow the air, steam, water, or like motive fluid to escape slowly, and thus allow the piston to return to its normal position, which allows the curtain to slowly unroll and close the 80 trap. The curtain being weighted and the actuating fluid being shut off, the weighted curtain acts through the roller C, pinion E, rack F, and piston-rod G and its attached piston to force the operating fluid through the 85 cock h. The object in allowing the curtain to unroll slowly is to prevent its descent before the cars have passed it.

What I claim is—

In a mine trap-door or curtain-operating 90 device, the combination with a roller and curtain, of a pinion on said roller, a cylinder and piston, a rack operated by the piston, a supply-valve for said cylinder, and means for controlling said valve, comprising a lever pivoted 95 secured upon one end of a rock-shaft mounted in proximity to the track-rail, a crank-arm on the opposite end of the shaft, and a spring located below said crank-arm, and a pitman connecting said crank-arm to 100 the valve-operating rod.

In testimony whereof I sign this specification, in the presence of two witnesses, this 15th day of October, 1897.

ALVIN HURFORD.
